UNITED STATES PATENT OFFICE.

CHARLES F. LOCKHART AND EVERETT H. ROBY, OF CLEVELAND, OHIO.

WASHING-MACHINE.

1,316,963.

Specification of Letters Patent. Patented Sept. 23, 1919.

Application filed March 22, 1919. Serial No. 284,382.

To all whom it may concern:

Be it known that we, CHARLES F. LOCKHART and EVERETT H. ROBY, citizens of the United States, residing at Cleveland, in the 5 county of Cuyahoga and State of Ohio, have invented certain new and useful Improvements in Washing-Machines, of which the following is a specification.

This invention relates to washing machines and has for its objects the provision of a machine which will be simple and efficient in operation, one which will wash clothes placed therein by suction instead of by the usual method of pounding or of 10 tumbling the clothes, one which will be cheap of manufacture, and one which, by the particular construction employed, will operate at a minimum expense. Other and 15 more limited objects of the invention will 20 become apparent from the following description:

In the drawings, Figure 1 is a vertical section through the machine constructed in accordance with our invention. Fig. 2 is a 25 plan view with part of the cover broken away. Fig. 3 is a horizontal section on the line 3—3 of Fig. 2. Fig. 4 is a sectional detail of one of the suction cups or bells and Fig. 5 is a sectional detail view of a clutch 30 employed to connect the certain parts to be described hereinafter.

The device comprises a tub 1 mounted upon legs 2 rigidly secured together by horizontal braces 3 and 4. Two of the legs, indicated at 2^a, are spaced apart from the tub to provide supports for a bearing 5 in which is reciprocally mounted a rod 6 having pivoted at its lower end a pitman 7 in turn connected to a crank shaft 8. A 35 pulley 9 is mounted on the aforesaid crank shaft and has driving connection through a belt 10 with a motor 11 mounted upon the horizontal braces 3. At its upper end the rod 6 has yieldingly mounted thereon an 40 arm 12, which overhangs the tub 1, and a rod 13 is fixed to the arm 12 in a manner to be described hereinafter.

Within the tub a basket 14, shown as composed of staves, is yieldingly supported 45 by springs 15 and 16 at the bottom and top

respectively. A cover 17 is fixed to the top by screws 18 and is provided with a hinged portion 19 to the top of which is secured a bearing 20 in which the rod 13 reciprocates. The clothes are placed within the 55 basket 14 and are operated upon by a plurality of suction bells 21 carried by a spider 22 affixed to the end of the shaft 13. The aforementioned bells comprise a frusto-conical portion 23 provided with a threaded 60 extension 24 by means of which they are secured to the spider 22. A ball check valve comprising a casting 25 provided with a seat 26 and a ball 27 is screwed in juxtaposition to the threaded extension 24, 65 and when the bell is forced against the clothes air within the bell is expelled through the valve and a vacuum is formed whereby the dirt is sucked from the clothes. The 70 spring 40 permits a certain amount of yielding movement to the arm 12.

To allow for the placing of the clothes within the basket the rod 13 is fitted at one end in a socket 28 in which the rod 13 is held by a latch 29, said latch comprising a 75 pin 30 having at one end a head 31 holding the shaft 13 in place, and at the other end an operating handle 32. A spring 33 is interposed between the head 31 and the bottom of the bore 35 formed in the arm 12 80 and normally holding the latch in closed position. By releasing the latch the arm 12 may be swung away from the rod 13, and the rod carrying with it the spider 22 is raised until it touches the inside of the 85 hinged cover 19 when the entire unit is swung back upon the hinges 38 to allow placing of the clothes in the basket.

We claim:

1. In a washing machine, the combination 90 of a covered tub, a clothes basket therein, springs between the tops of the tub and basket and the bottoms of the tub and basket respectively, a suction device located within the basket and having a rod extending 95 through the cover of the tub, and means to vibrate said rod and suction device up and down, said means including a swinging arm to which the rod is detachably connected.
2. In a washing machine, the combination 100

of a tub having a cover, a basket in the tub, springs between the bottom of the basket and the bottom of the tub, springs between the rim of the basket and the cover of the 5 tub, and a reciprocating pounder located in the basket, and having an operating rod extending through the cover of the tub.

Copies of this patent may be obtained for five cents each, by addressing the "Commissioner of Patents, Washington, D. C."

In testimony whereof, we do affix our signatures in presence of two witnesses.

CHARLES F. LOCKHART.
EVERETT H. ROBY.
